CLAIM

I claim the ornamental design for a television set assembly, as shown and described.

DESCRIPTION

FIG. 1 is a front perspective view of a television set assembly showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is another perspective view showing an example state of use wherein the front cover of the television set assembly is shown detached; and,

FIG. 10 is another perspective view showing an example state of use wherein the television set assembly is shown unfolded and propped up.

The broken lines in the figures depict portions of the television set assembly that form no part of the claimed design.
